UNITED STATES PATENT OFFICE.

ERNEST G. TURNER, OF LAKEWOOD, OHIO, ASSIGNOR TO AMERICAN SHIP BUILDING COMPANY, OF CLEVELAND, OHIO, & CORPORATION OF NEW JERSEY.

CONDENSING APPARATUS.

Application filed May 14, 1923. Serial No. 638,751.

The present improvements, relating as indicated to condensing apparatus, have more particular regard to jet condensing apparatus designed for use with engines of the reciprocating type employed in marine propulsion. One object of the invention is to create a higher vacuum in the low pressure cylinder and thereby increase the horse power of the engine at a reduced cost. I also aim to maintain such vacuum when the vessel is maneuvering either in rivers or in other places where the engines have to be operated at reduced speed, so that the ordinary vacuum producing means do not respond to the required purposes. Another object is to utilize a steam air ejector to heat the water in the feed and filter tank prior to its being pumped back to the boiler. Another incidental object is to remove the air from the feed water, this being accomplished in such feed and filter tank.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a transverse section more or less diagrammatic in character showing a partial cross-section of a vessel with engine for propelling same, such engine being connected with my present improved condensing apparatus; and Fig. 2 is a view similar to Fig. 1, but showing a modified form of such apparatus.

Referring first to the constructional form of apparatus shown in Fig. 1, the vertical reciprocating engine 1 there illustrated, it will be understood, is merely typical of various equivalent forms of engine that may be employed for the purpose of rotating the crank shaft 2 whereby the propeller of the vessel is driven. Leading from the cylinder of such engine is the main exhaust 3 that is connected at its lower end with a jet condenser 4 equipped with a series of sprays 5, by means of which water is discharged laterally inwardly into the upper portion of

such condenser. An additional centrally located jet 6, constituting a so-called pony injection is also located in such upper portion of condenser 4, and a vacuum breaker 4^a of usual type is attached to the condenser.

Said main jets 5 are adapted to be optionally connected, either with a low level injection intake 7 or a high level intake 8 in the side 9 of the vessel, through the medium of a pipe 10 having valve controlled branches 11 and 12 leading to such intake openings, respectively, an injection valve 13 in said pipe serving to control the supply of water to the annular chamber in the upper portion of condenser 4, from which the jets 5 open.

The lower end of said condenser is connected by means of an elbow joint 15 with a so-called Edwards air pump 16, the discharge line 17 from which leads to the overboard discharge opening 18. An air chamber 19 is connected with such line, while a check valve 18^a near its discharge end prevents a reverse flow of water therethrough.

Such air pump discharge line 17 has a valve-controlled branch 20 that is connected with a feed and filter tank 21, the outlet 80 therefrom discharging overboard, but at a lower level than the main outlet 18 of said line. Filter boxes 23 are arranged in the upper portion of said tank so that water as supplied through branch 20 is caused to flow 85 through said boxes in succession before overflowing into the main body of the tank. Said tank is provided with a valve-controlled drain connection 24 and with another valve-controlled connection 25 that 90 leads to a feed pump 26 that has a discharge through line 27 in turn connected with boilers (not shown).

An air ejector 30 is connected by means of a line 31 with the upper portion of condenser 4, as shown, such ejector being supplied with steam through a valve-controlled pipe 32 and draining to the feed and filter tank 21 through line 33.

Connected through elbow joint 15, or otherwise with the lower end of said condenser 4, are two independent valve-controlled suction lines 35 and 36 that respectively lead to a centrifugal pump 37 and a reciprocating pump 38. The discharge lines 39 and 40, that lead from said pumps are provided

with check valves, and the one thereof, viz, line 40, with a valve, and for convenience are united and have a single discharge connection 41 into the discharge line 17 that leads from air pump 16.

It will finally be noted that the feed and filter tank 21 is provided with an air vent 42 rising from the end thereof wherewith lines 20 and 33 are connected, such vent serving to eliminate the air from the feed water before it is carried through filters 23, and so entrained with the water withdrawn from the tank and fed to the boilers.

By attaching a jet condenser to the engine in the fashion just described, with a pump such as centrifugal pump 37 or reciprocating pump 38 connected with such condenser for removing the water of condensation therefrom, and an ejector 30 for removing air from said condenser, a higher vacuum can be created in the low pressure cylinder of said engine than is otherwise produced when the engine is operating at normal speed, and such vacuum can be readily maintained even when the engine is operating at low speed or is at a standstill, as in maneuvering. Thus the engine is enabled to operate at substantially maximum efficiency under conditions which would otherwise greatly reduce such efficiency, and even under normal operating conditions, due to the higher vacuum which can be maintained, the horse power of the engine may be measurably increased and the cost of operation reduced. Thus it may be assumed in the case of an engine of stated horse power that every inch of vacuum increase will increase the horse power of the engine approximately 50 horse power. The average vacuum which is obtained with a jet condenser is 22 inches, while with the air ejector 26 inches may be obtained, the resulting difference of four inches giving, in the assumed case, an increase of approximately 200 horse power. The amount of steam thus saved is considerably in excess of that required to operate the ejector, disregarding the fact that by having the discharge line from the ejector connected with the feed and filter tank a considerable portion of the heat of the steam used in such ejector is recovered in heating the water before it is pumped back to the boilers.

In contradistinction to the foregoing, with the old system the entire exhaust steam from the low pressure cylinder is admitted into the jet condenser and there mingles with the injection water which is brought to a temperature equal to the temperature of the low vacuum, viz, 152° F., where such vacuum stands at 22 inches as assumed above. The bulk of the injection water thus heated by the condensed steam is thrown overboard, only a small portion being ordinarily drawn off by a feed pump to the boiler, and such

portion of course being at the temperature last stated. With the present arrangement, on the contrary, I am enabled to raise the temperature of the water thus fed to the boiler to 170°, so that a marked economy is effected in this way.

In the modified construction illustrated in Fig. 2, substantially the same arrangement of jet condenser 4 and appurtenant parts is employed as in the previously described construction illustrated in Fig. 1. The use, however, of an air pump, such as the Edwards air pump 16, is done away with and the lower end of said jet condenser or rather the elbow joint 50 that constitutes a downward extension thereof similar to elbow joint 15 is directly connected with a centrifugal pump 51, and through a valve-controlled pipe 52 with a reciprocating pump 53, which pumps are adapted independently or conjointly to remove condensate from said condenser. Check valves, as in the case of corresponding pumps 37 and 38 in the previously described construction, are inserted in the discharge lines from said pumps 51 and 53 and these lines join in a common line 17 which as before leads to overboard discharge opening 18 and through a valve-controlled branch 20 to feed and filter tank 21.

The operation of the apparatus in such Fig. 2 will accordingly be seen to be substantially the same as that of Fig. 1 except that, due to the omission of the air pump, the centrifugal pump 51 is relied upon for the removal of the condensate under normal operating conditions, as well as under the special conditions to which reference has heretofore been made. When such special conditions are encountered, however, the reciprocating pump 53 may be additionally called into action in order to maintain the desired degree of vacuum in the condenser.

It will be obvious that various other arrangements of pumps and connections therefrom to the condenser may be employed in order to secure the desired effect without departing from the principle of my invention, or negativating the advantages obtainable by the proper operation of my improved apparatus. In such operation, it should be noted that the bulk of the injection water is discharged overboard and only a part into the feed and filter tank, the amount of such latter part being regulated so as to substantially equal the water sent to the boilers and no more, and this amount only being heated up to the higher temperature previously indicated.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In apparatus of the character described, the combination of a jet condenser, means 5 for drawing off condensate therefrom, means supplied by said condensate draw off means for filtering and accumulating feed water, and a steam jet air ejector exhausting from said jet condenser and discharging into 10 said feed water filtering and accumulating means, whereby the temperature in the water is raised.

2. In apparatus of the character described, the combination of a jet condenser, means 15 for drawing off condensate therefrom, a feed water filtering and accumulating tank supplied by said condensate draw off means, and a steam jet air ejector exhausting from said jet condenser and discharging into said 20 feed water filtering and accumulating tank, whereby the temperature in the latter is raised.

3. In apparatus of the character described, the combination of a jet condenser for receiving exhaust from main and auxiliary 25

engines, means for drawing off condensate from said jet condenser, a feed water filtering and accumulating tank supplied by said condensate draw off means, and a steam jet air ejector exhausting from said jet condenser and discharging into said feed water filtering and accumulating tank, whereby 20 the temperature in the latter is raised.

4. A condensing apparatus for a steam engine having in combination a jet condenser, an air pump connected for operation by said engine and normally serving to remove condensate from said condenser, two auxiliary independently operated pumps, one a centrifugal pump and the other a reciprocating piston pump, connected with said condenser for removing condensate therefrom, said pumps having a common outside discharge, a feed and filter tank, and a branch discharge connection from said pumps to 40 said tank, and an air ejector connected with said condenser, said ejector being connected to discharge into said tank.

Signed by me, this 11th day of May, 1923.
ERNEST G. TURNER.
